US0D1035491S

(12) **United States Design Patent** (10) **Patent No.:** **US D1,035,491 S**
(45) **Date of Patent:** **** Jul. 16, 2024**

(54) **SHUTTLE FOR MOBILITY**

(71) Applicants: **Hyundai Motor Company**, Seoul (KR); **Kia Corporation**, Seoul (KR)

(72) Inventors: **Joon Ho Lee**, Seoul (KR); **Seung Wook Ryu**, Seoul (KR)

(73) Assignees: **Hyundai Motor Company**, Seoul (KR); **Kia Corporation**, Seoul (KR)

(**) Term: **15 Years**

(21) Appl. No.: **29/831,279**

(22) Filed: **Mar. 18, 2022**

(30) **Foreign Application Priority Data**

Dec. 22, 2021 (KR) 30-2021-0061810

(57) **CLAIM**

The ornamental design for shuttle for mobility, as shown and described.

DESCRIPTION

FIG. 1 is a perspective view of the shuttle for mobility according to the present invention.

FIG. 2 is a front view of the shuttle for mobility of FIG. 1.

FIG. 3 is a rear view of the shuttle for mobility of FIG. 1.

FIG. 4 is a left side view of the shuttle for mobility of FIG. 1.

FIG. 5 is a right side view of the shuttle for mobility of FIG. 1; and,

FIG. 6 is a top view of the shuttle for mobility of FIG. 1.

1 Claim, 6 Drawing Sheets
